APPARATUS FOR MANUFACTURING THREAD
OR THE LIKEHayden B. Kline and Louis S. Fryer, Cleveland,
Ohio, assignors to Industrial Rayon Corpora-
tion, Cleveland, Ohio, a corporation of Delaware

Application November 12, 1936, Serial No. 110,460

8 Claims. (Cl. 18—8)

This invention relates to the manufacture of synthetic threads, filaments, bands, ribbons or the like, and, more particularly, to the manufacture thereof by a method in which the synthetic thread or the like is formed in a coagulating bath. The invention is applicable to the manufacture by a wet method of any synthetic thread, filament, band, ribbon or the like, an example being artificial silk thread manufactured according to a process, such as the viscose, cuprammonium, cellulose acetate or nitrocellulose process, in which a coagulating bath is or can be used. Staple fiber, artificial horsehair, artificial straw and similar products of relatively large denier requiring long periods of immersion in the coagulating bath to insure coagulation of the innermost portions thereof are examples of additional articles to the manufacture of which the invention is applicable. Other examples will readily occur to those skilled in the art to which the invention pertains.

By way of illustration, but in no sense of limitation, the invention will be described in connection with the manufacture of multiple filament artificial silk thread produced according to the viscose process. In this process, as in all processes by which artificial silk thread is produced by a wet method, the mass of material from which the thread is formed is extruded into a suitable bath wherein the thread is coagulated. If the thread is being produced in the conventional manner; i. e., according to either the spool spinning system or the pot spinning system, the thread after passing through the coagulating bath is collected, either on a rotating spool or in a rapidly rotating centrifuge, in suitable package form. If the thread is being produced according to a continuous system, it is passed, after being spun, to suitable devices on which it is subjected to various desired processing treatments, such as washing, desulphurizing, bleaching, oiling, etc., after which it is collected.

In producing multiple filament viscose artificial silk thread, it is the usual practice to withdraw the thread from the coagulating bath at a speed of from 60 to 80 meters per minute. Since for various reasons, as, for example, operating convenience, structural limitations, etc., the bath is relatively shallow, the depth of immersion of the spinneret below the surface is small and the time of immersion of the thread is correspondingly short. As a result, the thread is often incompletely coagulated when it leaves the bath. In the case of thread produced according to the spool spinning or pot spinning system, the coagulation proceeds while the thread is being wound or after it is wound into package form, not infrequently resulting in non-uniform coagulation. In the case of thread produced by a continuous process, it has been found desirable to provide means for alloying the coagulation to proceed to

substantial completion before subjecting the thread to the subsequent treatments.

It has been known heretofore that beneficial results with regard to the physical properties of the thread, especially the dyeing qualities, can be obtained by exposing the thread to the coagulating bath for a period long enough to insure substantially complete coagulation before it is collected and to that end numerous attempts have been made in the past to increase the period of immersion of the thread by increasing the length of travel of the thread in the bath. This, however, is rendered difficult by the limited space in the bath trough allowed by constructional limitations. Attempts to increase the thread travel in the bath have generally consisted of arrangements of guides or the like over which the thread has been drawn before leaving the bath. These have heretofore met with little success, however, because of excessive tensions imposed on the thread, difficulties in starting the thread through the guides or the like, lack of space, etc.

It is an object of the present invention to provide a long coagulating period for synthetic threads, filaments, bands, ribbons or the like by continuously storing a relatively long length thereof, preferably in the form of an advancing circular helix, in or in contact with the coagulating bath.

In the drawings, in which like reference numerals refer to like parts throughout, Figure 1 is a sectional elevation, from line 1—1 of Figure 2, of a conventional spool spinning apparatus equipped with the invention, parts being broken away to reveal constructional details; Figure 2 is an elevation of the same device from line 2—2 of Figure 1; Figure 3 is a sectional elevation on a larger scale from line 3—3 of Figure 4 of one form of thread-advancing thread store which may be used to advantage in the practice of this invention; Figure 4 is an end elevation of the device of Figure 3; Figure 5 is a sectional elevation of a pot spinning machine likewise equipped with the invention, parts being broken away to show details of construction; and Figure 6 shows the invention as applied to one form of continuous spinning machine of which only a portion is shown, other parts being broken away for the sake of clearness.

Referring now to the embodiment of the invention shown in Figures 1 and 2, the thread is formed in the usual manner by extrusion of the viscose from the spinneret 2 into a sulphuric acid coagulating bath 3 which is contained in trough 4 of a conventional spool spinning machine. In machines of this type there are a plurality of units disposed along a common bath trough, each consisting of a spinneret and its corresponding collecting spool; but for clarity only one such unit is shown. The viscose for each

spinneret is supplied through pipe 5 and mass tube 6 from a suitable source such as a supply line and pump (not shown). A guide 7 is preferably provided to guide the thread 1 from the spinneret 2 onto a unitary thread-advancing reel 8 shown completely submerged in the bath, although it might, if desired, be disposed in any one of a variety of positions, as later described.

On reel 8, the thread is subjected for a relatively long period of time to the action of the coagulating bath. This is done by temporarily storing a predetermined length thereof in a large number of closely spaced, generally helical turns which are formed and advanced axially along the reel 8 by the action of its elements during rotation. The thread 1, after leaving the reel 8, passes to the collecting spool 9 through its associated traverse guide 10. It is desirable to provide a guide 11 to prevent any tangling of the thread at the discharge end of reel 8 which may be caused by the motion of the traverse guide 10 of the spool 9, as illustrated by the extreme positions 10' of the guide 10 and corresponding positions 11' of the thread. In Figures 1 and 2 are shown guides 7 and 11 of suitable design, the operation of which will be explained more in detail hereinafter.

The reel 8 may be of substantially the same form and operate in the same manner as that shown, described and claimed in an application 30 entitled "Winding reel", Serial No. 652,089, filed January 16, 1933, by Walter F. Knebusch (Patent 2,210,914).

Referring to Figures 3 and 4, it can be seen that the reel is composed of two generally cylindrical members 12 and 13. Member 12, which may be termed the concentric member, is mounted on a drive shaft 14 with its axis concentric with that of the shaft 14 to which it is fixed for rotation by some means as a set screw 15. Its 45 periphery is composed of bar-like portions 16 between which are slots 17. Member 13, which may be termed the eccentric member, is mounted with its axis offset from and inclined to that of member 12 and is composed of a spider 18 rigidly supporting bars 19, which are disposed in slots 17 of member 12. The peripheries of members 12 and 13 contain the same number of bars, which number should preferably be as large as is possible consistent with the proper construction, operation and maintenance of the reel. Member 13 may be provided with a bearing portion, such as a sleeve 21 rotatably mounted on the cylindrical bushing 22 which may be so formed and supported on the frame member 23 that its axis 50 bears the aforesaid offset and askew relationship with regard to shaft 14.

Rotation of the shaft 14, which may be journaled in member 22, thus causes the concentric reel member 12, fastened to it, to rotate. Eccentric reel member 13 is rotated by contact of its bars 19 with the bars 16 of member 12. The offset and inclined relationship of reel members 12 and 13 causes the thread to progress in spaced helical turns axially along the reel in a manner more fully explained in said Knebusch application. Any desired predetermined length of thread, within reasonable limits, may thus be temporarily stored on a thread-advancing reel of this type by suitable construction thereof. Since the reel is supported at one end only, it is of cantilever form in the sense that the unsupported end is free of a projecting shaft, which feature provides convenience in starting the thread on the reel.

It is obvious, of course, that various other forms of thread-advancing reels, including those with shafts projecting at both ends, might be used in the practice of this invention in lieu of the type of reel shown in Figures 3 and 4.

It has been found advantageous under certain conditions to provide means for adjusting the position of the reel so that it may be disposed entirely below the surface of, partly immersed in, or wholly out of the bath. It may, for example, be desired to operate the reel while disposed partly within and partly without the bath. Also, it is somewhat more convenient for the operator, who can thus see while threading or starting the thread on the reel, to be able to move the reel to a position in which it is wholly out of the bath. For the purpose of providing adjustability, adaptability to conventional spinning machines, as well as portability for the purpose of cleaning, repairing, etc., the apparatus may be constructed as shown in Figures 1 and 2. The particular form of adjusting mechanism shown in Figures 1 and 2, however, forms no part of the present invention, being shown, claimed and described in application Serial No. 235,375, filed October 17, 1938, by Lavern J. Jordan.

In this embodiment of the invention, reel drive shaft 14, by means of which the reel 8 is rotated, is positively driven by some means as a gear 24 which may be driven through idler 26 by a pinion 27 rigidly mounted on a drive shaft 28, as, for example, by pin 29. Suitable means, as an electric motor 31, may be provided to rotate the drive shaft 28. Motor 31 may be mounted in alignment with shaft 28 on a frame 32 extending over the trough wall 33 on the apron 34 of the spinning machine, which apron 34 may be sloped as shown to drain any liquids spilled on it to the waste trough 35. Drive shaft 28 is journaled, as in bearing 36, in member 37 carried by frame 32, the upper portion of which member 37 may be curved as at 45 to provide a guide portion for the arm 38 mounted in the housing 39, in which is journaled drive shaft 28.

Housing 39 is formed integral with or otherwise rigidly fastened to the frame member 23, which supports reel 8 and the gears that drive it from shaft 28, and is adapted to be swung about shaft 28 as an axis. Arm 38, which is rigidly mounted on the housing 39, bears a handle assembly 41 containing a spring 42 and plunger 43 by means of which the reel is held in the position corresponding to any of the holes 44 in the curved periphery 45 of the member 37. It is desirable to provide means such as roller 46, rotatably mounted on arm 38, and roller 47, rotatably mounted on the bracket 48, to support the load exerted by the weight of the reel 8 and its supporting and driving means which would otherwise tend to bend the drive shaft 28. A supporting bracket 49 may also be provided for this purpose. A shield 51 may be provided to protect the reel from any turbulence that might otherwise be set up by rotation of the gears.

The desirability of guiding the thread as it contacts and leaves the reel is just as great when the reel is swung to the various other previously mentioned positions as when it is wholly submerged. However, when the reel is disposed in these other positions, the thread contacts and leaves the reel at angular positions different from those at the lowermost reel position. This is illustrated by broken lines 1' of Figure 2, which indicate the angular positions of the thread with

respect to the reel when the latter is in position 8' above the surface of the bath.

For these reasons the guides 7 and 11 may be of the design shown, in which they are curved and mounted on the housing 39, as by lugs 52 and 53, so that they bear the same relationship to the reel 8 in all positions. It will be observed that the guides perform their function throughout the entire range of positions of the reel. That is, as the points at which the thread contacts and leaves the reel change, and consequently the angular position of the thread with respect to the reel changes, the thread slides along each guide to the new position as is illustrated by the position of the thread 1 with respect to the guides 7 and 11 corresponding to reel position 8' of Figure 2.

In the operation of apparatus of the character shown in Figures 1 and 2, the operator, by means of the adjusting handle 41, first swings the reel up and completely out of the bath to a position such as that indicated at 8' and starts the motor 31. He then seizes the end of the thread 1 formed by the mass issuing from the spinneret 2 disposed in coagulating bath 3, passes the thread through guide 7 and starts it on the reel 8 by winding it one or two turns around the reel. Because the thread is wet, it readily adheres to the reel. Because of the action of the reel as it rotates, the thread forms spaced helical turns on the reel which are advanced axially of the reel and finally discharged from the unsupported end thereof. The operator seizes the end of the thread as or after it discharges, leads it past guide 11 and starts it on the take-up device, in this case the spool 9 and traverse guide 10. The reel is then swung into the bath until it assumes the desired position, whether wholly or partly immersed.

In the embodiment of the invention shown in Figure 5, the thread 1, after being formed in the usual manner by extrusion of the viscose from the spinneret 2 into the coagulating bath 3 contained in trough 4, passes to the reel 8, on which a predetermined length is continuously stored in the form of an advancing helix for the purposes of providing a relatively long period of immersion of the thread in the bath. The thread, after leaving reel 8, then passes around the conventional godet wheel 54, which may be rotated by some means as gears 60, through the funnel 55 and thence to the rapidly rotating spinning pot 56. Funnel 55, which is reciprocated vertically by suitable means (not shown), imparts a twist to the thread as it leaves the bottom edge of the funnel and causes the thread to be wound in the form of a cake in the pot in the usual manner. The pot 56 is rotated at the desired high speed by some means as a motor 57. The viscose may be supplied to the spinneret 60 through pipe 5 and mass tube 6 from a suitable source such as a supply pipe and pump (not shown). Guides 7' and 11' may be provided, if desired, to guide the thread as it contacts and leaves the thread-storage device 8.

The reel 8 may be mounted and driven as shown in Figures 1 and 2 or in some other manner, as, for instance, that illustrated in Figure 5, in which the reel is built in as part of the machine. In the embodiment illustrated, the 70 bushing 22, on which is mounted the eccentric member of the reel and in which is journaled the drive shaft 14, is positioned on the frame member 23 which is suitably mounted with a liquid-tight joint on the bath-trough wall 58. 75

Frame member 23 is formed with a tubular portion extending through the trough wall, as shown. In the frame member 23 may be positioned a rubber or other suitable bearing 59 for shaft 14. The rubber bearing 59 acts as a seal, but liquid which seeps through between the shaft 14 and the bearing 59 may be collected in a suitable collecting trough 61 which in the case shown is designed to extend under the outer ends of the bearings of all the reels on the machine and from which the liquid may be returned to the recirculating system.

An outer bearing 62 may be provided to support the end of the shaft 14 and bear the thrust 15 of the bevel gear 63 which drives reel shaft 14 and is driven by gear 64 mounted on drive shaft 65, which may be common to all reels disposed in the trough 4 and which may be driven by any suitable means (not shown). The bracket which supports bearing 62 may also support the trough 61. A deflecting disc-like member 66 may be mounted on shaft 14 to prevent any liquid which may seep through bearing 59 from traveling along shaft 14 to bearing 62. It is obvious, of course, that various other means for mounting the reel 8 and its driving mechanism and sealing the drive shaft 14 may be provided without departing from the spirit of the invention.

The invention is shown in Figure 6 as applied to a continuous processing machine. The machine illustrated is a modification of that shown, described and claimed in an application entitled "Manufacture of artificial silk," Serial No. 7,114, filed February 18, 1935 by Walter F. Knebusch and Alden H. Burkholder (Patent 2,225,642) to which reference may be made for a more complete description. In the operation of the machine shown, the thread 1 is formed in the usual manner by extrusion of the viscose from the spinneret 2 into the coagulating bath 3 contained in trough 4. To allow coagulation to proceed to substantial completion, a predetermined length of the thread is then continuously temporarily stored in a plurality of spaced helical turns on a reel 8a after which it passes over the roller 67 or other means for changing the direction of the thread to the first of a series of such reels on which various processing treatments may be performed on the thread. The latter may be of a type similar to that previously described. Guides 7' and 11' may be provided, if desired, to guide the thread 1 as it contacts and leaves the reel 8a.

The reels of the series, of which only three are shown and which bear numbers 68, 68a and 68b, are arranged in the manner shown in stepped relationship with the thread-receiving end of each reel other than the first directly beneath the thread discharge end of the preceding reel. The unsupported ends of the reels are therefore all presented to an operator at the front of the machine and the helical turns of thread progress to the front of all reels. The thread stored on each reel is subjected to treatment by some such apparatus as that shown which comprises a suitable reagent distributor 69 which is supplied by reagent from a supply pipe 71. The reagent is showered down on the thread on the reel by the reagent distributor 69 and collected in a trough 72. Since a machine of this type may comprise a plurality of such series of reels, of which all reels in the corresponding positions are used for the same processing treatments, the reagent supply pipes 71 and collecting troughs

72 may be common to all reels in the corresponding positions.

As examples of possible processing treatments which may be applied to the thread in a machine of this type, the thread, by the use of suitable reagents, may be washed on reel 68, desulphurized on reel 68a, bleached on reel 68b and so on, as many reels being used as are required to obtain the desired processing treatments, the thread finally being collected by a suitable device. The processing reels may be driven by suitable means as that shown comprising a main drive shaft 73 provided at intervals with helical gears 74 each of which drives a helical gear 75 connected by a shaft 76 through adjustable change speed gears 77 to a shaft 78 extending lengthwise of the machine and arranged to drive corresponding reels in different series. In the machine shown, a plurality of reels in adjacent series in the corresponding positions are mounted on and driven from the housing 79 in which is disposed the shaft 78 from which each reel is driven by means of a helical gear 81 mounted for rotation with shaft 78 and meshing with gear 82 which is connected to the reel drive shaft 14 as by clutch 83.

The manner of mounting and driving the reel 8a immersed in the coagulating bath may be similar to that shown in Figure 5 and no detailed description is therefore required. The drive shaft 65, which rotates the gears 63 and 64 which in turn rotate each coagulating reel 8, may be driven by some means such as gear 84, shown in broken lines, adapted to be driven through change gears 85 from helical gears similar to 74 and 75 which are contained in a housing 91 and which are driven from the main drive shaft 73. The shaft 86, from which each spinneret pump 87 is actuated, may be rotated by some means such as a change gear box 88 by which adjustment of the pump delivery may be facilitated, and which may be driven, as by chain 89, from the gears in the housing 91.

It is obvious that various changes and modifications may be made in the embodiments herein shown and that numerous other embodiments may be devised without in any way departing from the spirit of the invention. For instance, though the reels are shown in all the embodiments as completely submerged in the bath, each may be so disposed that it is largely, but not entirely, immersed in the bath or even disposed so that it only dips into the bath to a relatively slight extent. Likewise a plurality of reels disposed entirely in or partly in the bath may be used. Various other means of mounting and driving the coagulating reels other than those shown may be provided. The reels may be mounted in various other positions in the bath. For instance, they may be mounted with their axes parallel or at an acute angle to the longitudinal trough walls rather than at right angles as shown.

With thread or the like of sufficient strength, it may not be necessary to supply means for positively driving the coagulating reel since the reel may be rotated and operated by the pull of the thread or the like as it is drawn off of the reel.

Although the invention has been shown and described with reference to the use of devices such as rotating spools, as in Figures 1 and 2, rotating pots and godet wheels, as in Figure 5, and rotating thread-advancing reels, as in Figure 6, for collecting or withdrawing the thread or the like, it should not be construed as lim-

ited thereto: various other kinds of collecting or withdrawing means may be used instead. In the manufacture of staple fiber, for example, which may be readily produced according to the present invention, the thread bundle is often collected on a skeining reel. Likewise, various improved forms of apparatus have been devised for producing staple fiber by continuous processes wherein the thread bundles are passed from the coagulating bath through treating devices and to cutting means: the invention may be readily applied to apparatus of these and other types.

Stretch spinning, which under certain conditions is beneficial because it provides increased tensile strength and decreased elongation, may be readily accomplished by several methods according to this invention.

As examples, the reel may be so constructed that its diameter progressively increases from the receiving to the thread discharge end, in which case a limited amount of stretching is obtained as the thread or the like travels across the reel. Under such circumstances, a flared reel of the type identified by reference character 8a in Figure 6 may advantageously be substituted for the generally cylindrical reels 8 employed in the embodiments of the invention illustrated in Figures 1, 2 and 5. Also, by rotating the reel at a suitable speed so the thread or the like will be drawn from the spinneret at a rate greater than that at which it is extruded, stretch spinning effects may be obtained.

In addition, stretch spinning effects may be obtained in the case of the spool spinning system by rotating the spool at a speed which tends to draw the thread or the like from the reel more rapidly than it is discharged from the reel. In the case of the pot-spinning system, a similar stretch effect can be obtained by regulation of the relative speeds of the godet wheel and the coagulating reel. In the continuous spinning system, a like effect may be obtained by suitably regulating the speed at which the thread or the like is drawn from the coagulating reel, as by the following reel.

It is obvious that various modifications in the reel herein described may be devised; also, that any other unitary thread-advancing thread store device may be used on which the thread or the like by the action of the elements thereof is caused to advance in spaced helical turns. Other modifications and advantages of the invention will be apparent to those skilled in the art. It is to be understood that the invention is not restricted only to the manufacture of multiple filament artificial silk thread, for, as has been previously mentioned, it may be used in conjunction with the manufacture by a wet method of any synthetic thread, filament, band, ribbon or the like in which it is desirable to obtain a long travel of thread or the like in the coagulating bath. In the appended claims "thread or the like" is intended to refer generically to threads, filaments, ribbons, bands and like articles.

It is intended that the patent shall cover, by suitable expression in the appended claims, whatever features of patentable novelty reside in the invention.

What is claimed is:

1. Apparatus for the manufacture of thread or the like comprising a coagulating bath; a spinning nozzle in said coagulating bath; a unitary, self-threading thread-advancing thread store device to which the thread or the like

passes from said spinning nozzle and over the periphery of which it is positively advanced in a large number of closely spaced generally helical turns while being subjected to the action of said coagulating bath in a length sufficiently great to permit substantially complete coagulation of the thread or the like to be achieved before it is discharged from said thread store device; means for adjustably supporting said thread store device independently of the position of said spinning nozzle whereby said thread store device may be positioned in a plurality of positions ranging from one in which it is disposed entirely out of said coagulating bath to one in which it is immersed in part at least in said coagulating bath; means for rotating said thread-advancing thread store device as a unit in each of its different positions as well as during movement of said thread store device from position to position; and take-up means to which the thread or the like passes from said thread store device.

2. Apparatus for the manufacture of thread or the like comprising a coagulating bath; a spinning nozzle in said coagulating bath; a unitary, self-threading thread-advancing thread store device to which the thread or the like passes from said spinning nozzle and over the periphery of which it is positively advanced in a large number of closely spaced generally helical turns while being subjected to the action of said coagulating bath in a length sufficiently great to permit substantially complete coagulation of the thread or the like to be achieved before the thread or the like is discharged from said thread store device; means for adjustably supporting said thread store device independently of the position of said spinning nozzle whereby said thread store device may be positioned in a plurality of positions ranging from one in which it is disposed entirely out of said coagulating bath to one in which it is immersed in part at least in said coagulating bath; and take-up means to which the thread or the like passes from said thread store device.

3. Apparatus for the manufacture of thread or the like comprising a coagulating bath; a unitary, self-threading thread-advancing thread store device of cantilever construction wholly immersed in said coagulating bath over the periphery of which, from the supported to the unsupported end thereof, the thread or the like is positively advanced in a large number of closely spaced generally helical turns, said thread store device serving to subject to the action of said coagulating bath a length of thread or the like long enough to permit substantially complete coagulation of the thread or the like to be achieved before the thread or the like is discharged from said thread store device; means operated from a power source outside of said coagulating bath for rotating said thread-advancing thread store device as a unit, said means being disposed below the level of liquid in said coagulating bath and, disposed outside of said coagulating bath, take-up means to which the thread or the like passes from the unsupported end of said thread-advancing thread store device.

4. Apparatus comprising a source of thread or the like; a processing bath; a unitary, self-threading thread-advancing thread store device of cantilever construction wholly immersed in said processing bath over the periphery of which,

from the supported to the unsupported end thereof, the thread or the like is positively advanced in a large number of closely spaced generally helical turns, said thread store device serving to subject to the action of the processing bath a length of thread or the like long enough to permit substantially complete processing of the thread or the like to be achieved before the thread or the like is discharged from said thread store device; means operated from a power source outside of said processing bath for rotating said thread-advancing thread store device as a unit, said means being disposed below the level of liquid in said processing bath and, disposed outside of said processing bath, take-up means to which the thread or the like passes from the unsupported end of said thread-advancing thread store device.

5. Apparatus comprising a source of thread or the like; a processing bath; a unitary, self-threading thread-advancing thread store device to which the thread or the like passes from said source and over the periphery of which it is positively advanced in a large number of closely spaced generally helical turns while being subjected to the action of said processing bath in a length sufficiently great to permit substantially complete processing of the thread or the like to be achieved before the thread or the like is discharged from said thread store device; means for adjustably supporting said thread store device whereby said thread store device may be positioned in a plurality of positions ranging from one in which it is disposed entirely out of said processing bath to one in which it is immersed in part at least in said processing bath; and take-up means to which the thread or the like passes from said thread store device.

6. Apparatus comprising a source of thread or the like; a processing bath; a unitary, self-threading thread-advancing thread store device to which the thread or the like passes from said source and over the periphery of which it is positively advanced in a large number of closely spaced generally helical turns while being subjected to the action of said processing bath in a length sufficiently great to permit substantially complete processing of the thread or the like to be achieved before it is discharged from said thread store device; means for adjustably supporting said thread store device whereby said thread store device may be positioned in a plurality of positions ranging from one in which it is disposed entirely out of said processing bath to one in which it is immersed in part at least in said processing bath; means for rotating said thread-advancing thread store device as a unit in each of its different positions as well as during movement of said thread store device from position to position; and take-up means to which the thread or the like passes from said thread store device.

7. Apparatus of the character described in claim 4 in which the thread-advancing thread store device is characterized by a periphery which is flared over at least part of its length in the direction of travel of the thread or the like.

8. Apparatus of the character described in claim 5 in which the thread-advancing thread store device is characterized by a periphery which is flared over at least part of its length in the direction of travel of the thread or the like.

HAYDEN B. KLINE.

CERTIFICATE OF CORRECTION.

Patent No. 2,241,725.

May 13, 1941.

HAYDEN B. KLINE, ET AL.

It is hereby certified that error appears in the printed specification of the above numbered patent requiring correction as follows: Page 1, second column, line 39, after the word "store" insert --device--; page 4, first column, line 32, for the reference numeral "8" read --8a--; page 5, first column, line 65, and second column, line 14, claims 3 and 4 respectively, after "bath" insert a semicolon; and that the said Letters Patent should be read with this correction therein that the same may conform to the record of the case in the Patent Office.

Signed and sealed this 29th day of July, A. D. 1941.

Henry Van Arsdale,

Acting Commissioner of Patents.
